UNITED STATES PATENT OFFICE.

SYLVANUS T. MURCHIE, OF KAUKAUNA, WISCONSIN, ASSIGNOR TO THE UNION BAG & PAPER COMPANY, OF JERSEY CITY, NEW JERSEY, A CORPORATION OF NEW JERSEY.

PAPER-BAG MACHINE.

SPECIFICATION forming part of Letters Patent No. 718,143, dated January 13, 1903.

Application filed June 4, 1901. Serial No. 63,102. (No model.)

To all whom it may concern:

Be it known that I, SYLVANUS T. MURCHIE, a citizen of the United States of America, residing in Kaukauna, in the county of Outagamie, in the State of Wisconsin, have invented certain new and useful Improvements in Paper-Bag Machines, of which the following is a true and exact description, reference being had to the accompanying drawings, which form a part thereof.

My invention relates to paper-bag machines, and, as shown, is particularly, though not exclusively, designed for use in connection with and as an improvement upon such machines as are described in my prior patents, Nos. 585,280, of June 29, 1897, and 587,135, of July 27, 1897, the object of my present invention being to provide in connection with distending-rolls, whether suction-rolls or otherwise, gripping-fingers which will move to engage and disengage the blanks with great ease, rapidity, and accuracy, the leading feature of my invention consisting in securing the gripping-fingers to the longer arms of pivoted levers secured to the distending-rolls or parts moving therewith and extending past the centers of the said rollers, the shorter arms of such levers being acted on to move the fingers.

The nature of my improvements as a whole will be best understood as described in connection with the drawings in which they are illustrated, and in which—

Figure 1 is a plan view of a part of a paper-bag machine embodying my invention. Fig. 2 is a side elevation on the section-line 2 2 of Fig. 1. Fig. 3 is a front view. Fig. 4 is a section on the line 4 4 of Fig. 2, and Fig. 5 is a view showing a modification in the construction of the finger-carrying lever and its attachment to the shaft of a distending-roll.

A and A' indicate the side frames of the machine, connected, as shown in the part of the machine illustrated, by a cross-bar A².

B B and C C are feed-rolls.

D D and D' D' are cam-rollers secured on the shafts of the feed-rolls C C and having

lateral cam-surfaces, (indicated at d d and d' d').

E E indicate the distending-rolls, which, as illustrated, are suction-rolls having hollow shafts E', connecting through air-tight bearings in the frame A with the branches F' F' of the suction-pipe F.

G is a feeding and pressing roll which, in connection with the lower distending-roll E, withdraws the blank and presses out the diamond fold after it is formed by the distending-rolls. As shown in the construction illustrated in Figs. 1 to 4 inclusive, the shafts E' of the hollow studs, indicated at E², (best shown in Figs. 2 and 4,) extend through them. The rolls are also provided with perforations, (indicated at E³, Fig. 4,) and the shafts with bearings, (indicated at E⁴.)

H indicates the train of gear-wheels, by which the various parts are connected together and which being of usual construction need not be particularly described.

I I and i i are levers pivoted eccentrically in the hollow studs E E and extending, as shown, through the shaft, I' indicating the shorter ends of the levers, and I² the pivots upon which they turn.

I³ i³ indicate the gripping-fingers, secured to the longer ends of the levers I, and it will be noticed that the shorter ends of the levers are provided with longitudinally-extending slots at their ends.

J is a plunger working in the perforations E³ and pressed out by a spring J' against the shorter ends of the finger-carrying levers, the action of the spring tending to press the shouldered end of the lever out and throw the longer end of the lever with the finger in and into position to engage the bellows-folded blank.

K is a plunger working in the bearing E⁴ and connected with the slotted end I' of the lever I by a pin K'.

L L and l l are studs or pillars extending upward from the cross-bar A² and having pivoted upon their upper ends the levers M M' and m m', said levers being eccentrically

pivoted and having cam-rollers $M^2 m^2$ resting against the cams $d d'$ of the cam-rolls $D D'$, the longer ends of the said levers having attached to them the annular plates $M^3 m^3$, which extend around the hollow shafts $E' E'$ and rest against the plungers $K K$.

The operation of the device is easily followed. When the cam-surfaces d and d' are in contact with the cam-rollers of the levers M and m , the plates $M^3 m^3$ are pressed in toward the distending-rolls and, acting through the plungers $K K$, they press the shorter ends of the levers I inward, pressing the springs J' and throwing the fingers $I^3 i^3$ out of operative position. The recessed portions of the cams are arranged so as to come into operation at the proper time for throwing the fingers in, and as soon as the cam-rolls pass over the edge of the elevated portion of the cam the springs J' come into active operation, forcing the shorter ends of the levers I i out and the longer ends in, the eccentric pivoting of the levers I M permitting this to occur with great rapidity, and obviously the same construction causes the withdrawal of the fingers with equal rapidity when the elevated portion of the cam again comes into operation on the cam-rolls.

In Fig. 5 I have illustrated a modification in which instead of having a hollow stud passing through the hollow shaft of the distending-roll I form the finger-lever with an annular center, (indicated at I^4), which passes around the hollow shaft and is pivoted thereto by pivot-screws I^5 , as shown. Obviously the operation of this device is in all respects the same as that shown in the other figures of the drawings.

I am aware that pivoted gripping-fingers acting on a bag-blank as do my fingers have heretofore been employed; but by securing my fingers on levers eccentrically pivoted, as described, and extending past the centers of the rolls I am enabled at the same time to secure great rapidity in the action of the fingers and great ease in their operation. To explain: It is of course obvious that the speed of movement of the gripping-fingers, other factors remaining constant, will be determined by the relative lengths of the short and long arms of the pivoted lever to which the finger is attached. Again, it is clear that it is not advisable to make the shorter lever-arm unduly short, and assuming that this arm is given its minimum length consistent with good mechanics the speed of movement of the finger on the end of the long lever-arm will be determined by the length of the lever as a whole. Now by my new construction, in which I carry the lever across the center of the roll, I am enabled to use a much longer finger-lever than was possible in older constructions, in which the lever lay entirely on one side of the roll-center, and consequently my construction makes it possible to

give the finger a more rapid movement; but the shorter the lesser arm of the lever is made the more power is required to move it and the greater the strains to which the pivot and connected parts are exposed. Hence by increasing the length of the lever, leaving the proportion of the arms the same, the strain will obviously be diminished, and my novel construction enables me to secure the maximum desirable rapidity with the least possible strain, as it enables me at the same time to increase the actual length of the shorter lever-arm and to decrease its proportional length to the longer arm. For these reasons my machine combines great rapidity and ease of operation.

Having now described my invention, what I claim as new, and desire to secure by Letters Patent, is—

1. In a paper-bag machine, the combination with distending-rolls of levers pivoted eccentrically on each side of the rolls and extending past the centers thereof, fingers secured to the longer ends of said levers adapted to clamp the blanks to the roll in one position of the levers and means for actuating said levers to engage and disengage the blanks as the rolls revolve, said means acting on the shorter ends of the levers.

2. In a paper-bag machine, the combination with distending-rolls of levers pivoted eccentrically on each side of the rolls and extending past the centers thereof, fingers secured to the longer ends of said levers adapted to clamp the blanks to the roll in one position of the levers, springs acting on the shorter ends of the levers to move the fingers into engaging position and cam-actuated mechanism acting also on the shorter ends of the levers to move and hold the fingers out of operation.

3. In a paper-bag machine, the combination with distending-rolls of levers pivoted eccentrically on each side of the shaft and extending substantially from side to side of the rolls, fingers secured on the longer ends of the levers and adapted to clamp the corners of a bellows-folded blank thereto, annular plates, as M^3 , arranged to act against the shorter ends of the levers and cam mechanism for moving the plates toward and away from the ends of the rolls.

4. In a paper-bag machine, the combination with distending-rolls of levers pivoted eccentrically on each side of the shaft and extending substantially from side to side of the rolls, fingers secured on the longer ends of the levers and adapted to clamp the corners of a bellows-folded blank thereto, annular plates, as M^3 , arranged to act against the shorter ends of the levers, pivoted levers to which said annular plates are secured and cams acting on said levers to move the plates and finger-levers.

5. In a paper-bag machine, the combination with distending-rolls of levers pivoted eccen-

trically on each side of the shaft and extending substantially from side to side of the rolls, fingers secured on the longer ends of the levers and adapted to clamp the corners of a bellows-folded blank thereto, annular plates, as M³, arranged to act against the shorter ends of the levers, eccentrically-pivoted levers to the longer ends of which said annular plates

are secured and cams acting on the shorter ends of said levers to move the plates and finger-levers.
